Intellectual Property(57) **CLAIM**

The ornamental design for a respirator helmet, as shown and described.

DESCRIPTION

FIG. 1 is a first perspective view of a respirator helmet according to the new invention.

FIG. 2 is a left side view of the respirator helmet of FIG. 1.

FIG. 3 is a right side view of the respirator helmet of FIG. 1.

FIG. 4 is a front view of the respirator helmet of FIG. 1.

FIG. 5 is a rear view of the respirator helmet of FIG. 1.

FIG. 6 is a top view of the respirator helmet of FIG. 1; and,

FIG. 7 is a bottom view of the respirator helmet of FIG. 1. The broken lines shown in the drawings depict portions of the respirator helmet that form no part of the claimed design.

1 Claim, 7 Drawing Sheets(56)
